UNITED STATES PATENT OFFICE

2,091,377

BOX-MAKING MACHINE

Alfred L. Rosenmund, Rockaway, N. J., assignor
to Stapling Machines Co., a corporation of
Delaware

Application February 4, 1936, Serial No. 62,272

16 Claims. (Cl. 140—93)

This invention relates to machines for equipping wired box parts with interengageable fasteners and particularly to machines for manipulating a wire secured to a box part to provide the wire end with a bight and to perpetuate the bight by driving the end of the wire into the box part.

It is an object of the invention to provide certain improvements in machines of the type shown and described in U. S. Patents No. 1,933,031 of October 31, 1933, and No. 2,024,188 of December 17, 1935.

It is a further object to provide a machine of the character described with improved means for clinching the ends of wires which are driven through the box parts.

One illustrative embodiment of the invention is shown in the accompanying drawings, in which:—

20 Figure 1 is a side elevation of a machine embodying the invention.

Fig. 2 is a rear elevation of the same.

Fig. 3 is a diagrammatic view of the wire-manipulating elements of the machine shown in stopped position with a pair of wire-connected box parts positioned on the supporting table. The dotted lines indicate the table in raised position and the full lines indicate the table in lowered position.

30 Fig. 4 is a similar view at a different stage in the cycle of operation and showing the position of the different wire-manipulating elements at the time of a prong-forming operation which occurs just after the wire-cutting operation.

35 Fig. 5 is a similar view showing the position of the wire-manipulating elements after the wire connecting the two box parts has been severed and prongs formed on the ends of the severed wires and after the prongs have been swung over 40 onto their respective box parts to form bights.

Fig. 6 is a similar view showing the position of the box parts after the prongs have been driven through the box parts and clinched to perpetuate the bights.

45 Fig. 7 is an enlarged perspective view of one of the clinching units. In this view the prong on the end of the wire is being driven through the box part and has not yet contacted the clincher block.

50 Fig. 8 is a similar view but showing the position of the parts upon completion of a clinching operation.

Fig. 9 is a perspective view of a wirebound box blank equipped with interengageable fasteners 55 by the machine of this application.

Fig. 10 is a perspective view of a completed box equipped with interengageable fasteners by the machine of this application and showing one of the fasteners in an intermediate stage of interengagement and the other fasteners completely interengaged. 5

One illustrative product of the machine of this application is shown in Figs. 9 and 10. Fig. 9 discloses a wirebound box blank consisting of a plurality of sections of cleats A and side sheets B connected together by binding wires C stapled to the several sections. Such wirebound box blanks are made on a box blank machine which staples the wires to the several sections. As successive box blanks emerge from the box blank machine they are connected by the binding wires C, appropriate spaces being left between successive box blanks to permit severing the wires and manipulating the severed ends to provide bights D (see Fig. 9) which bights may be interengaged 20 to close the box, as shown in Fig. 10.

As the wire-connected box blanks emerge from the box blank machine they are fed into the machine of this application and positioned on a vertically movable support or table T, as shown 25 diagrammatically in Fig. 3. As there shown, in dotted lines, the wire to be operated upon is located directly above cutters 1, prong-forming blocks 2, and bight-forming spindles 3, and below cutter-actuator 4 carrying prong-forming elements 5, and also below drivers 6. 30

In Fig. 3, the parts are at rest preparatory to the start of the machine. The machine is operated through a one-cycle clutch as explained in said Patents No. 1,933,031 and No. 2,024,188, 35 and during one cycle of operation the several wire-manipulating elements go through the successive operations shown diagrammatically in Figs. 3 to 6.

As shown in Fig. 3 in the full lines, the table 40 support first lowers the wire C between cutters 1 and into contact with prong-forming blocks 2. As shown in Fig. 4, the cutter-actuator 4 carrying prong-forming elements 5 descends, operating the cutters 1 to sever the wire C and bend the severed 45 ends over prong-forming blocks 2 to form prongs P on the ends of the wire. After descent of the cutter-actuator, the spindles 3 are raised so that the wire will be lifted clear of the prong-forming blocks. The spindles are then partially rotated 50 to swing the prongs over onto the box parts, as shown in Fig. 5. Drivers 6 thereupon descend and drive the prongs through the box parts to perpetuate the bights, as shown in Fig. 6.

The several wire-manipulating elements and 55

the mechanisms for operating the same are disclosed and described in detail in said Patents No. 1,933,031 and No. 2,024,188, reference to which is hereby made for a detailed description.

5 The present invention is directed to an improvement in the mechanism for clinching the prongs P which are driven through the box parts.

In the machines of the prior patents referred to, the box part during a driving operation rests 10 upon a plate yieldingly held by means of springs a sufficient distance above the clincher block to permit the prong to be driven through the box part before contacting with the clincher block, an opening being provided in the plate above the 15 clincher block. The springs are of such stiffness as to resist the thrust of the driver while the prong is being driven through the box part and then to yield to the thrust of the driver to permit it to force the prong down against the clincher 20 block to cause a clinching operation.

While such an arrangement operated satisfactorily under certain conditions, it has been found difficult to regulate the stiffness of the springs to accommodate different types of wood employed 25 in the manufacture of boxes. Springs having sufficient stiffness to resist the thrust of the driver when driving a prong through soft wood sometimes fail to resist the thrust of the driver when driving prongs through harder woods, with 30 the result that the prongs are crushed or flattened on top of the box part instead of being driven therethrough.

The present invention is intended to eliminate the difficulties referred to above and to provide 35 positive means for resisting the thrust of the driver until the prong has been driven through the box part, and to provide means for automatically withdrawing the positive resistor after the prong has been driven through the box part 40 to permit the driver to drive the prong downwardly against the clincher block, thus providing clincher mechanism adapted without adjustment to operate satisfactorily on woods varying widely in hardness.

45 Referring particularly to Figs. 7 and 8, the box part designated X rests during a driving operation on a plate or plates 10, there being one plate 10 for each wire secured to the box part X. Plate 10 is supported above blocks 11 and in 50 spaced relation thereto by means of springs 12 and bolts 13 slidable in recesses formed in block 11. Block 11 is secured to one of the machine castings, as described in the afore-mentioned patents.

55 Plate 10 is provided with an opening 14 passing therethrough and into which the prong P may be driven by the driver. Directly beneath the opening 14 and secured to the upper surface of the block 11 is a clincher block 15. As shown in 60 Fig. 7, the clinching surface of the block 15 is located a sufficient distance below the top surface of the plate 10 to permit the prong to be fully driven before it contacts with the block 15.

To positively hold the plate 10 in raised position during the driving of the prong, plate 10 is provided with a downwardly extending lug 16 which normally rests upon a cam 17 fixed to a 65 shaft 18 journaled in bearings in a block 19 secured to block 11.

70 As shown in Fig. 7, cam 17 is normally held in contact with lug 16 positively to keep plate 10 in raised position through the action of a spring 20, one end of which is secured to a bracket 21 carried by block 11, and the other end of which 75 is secured to a pin 22 fixed to shaft 18. Cam 17

carries a pin 23 to limit the action of spring 20 and to position the cam 17 relative to the lug 16.

Thus it will be seen that when the cam 17 is in the position shown in Fig. 7, plate 10 will be held positively in raised position during the driving of the prong P through the box part X. Drivers 6 which drive the prongs through the box part are carried by a vertically reciprocating cross bar 24, as shown in Fig. 2. To move cam 17 out of contact with lug 16 at the proper time 10 to permit the driver to force the prong P down against clincher block 15, there is secured to cross bar 24 a casting 25 carrying a downwardly extending release bar 26 which is so adjusted as to contact a lever 27 fixed to shaft 18 just as the 15 driver contacts the prong and then starts to drive the prong through the box blank. Continued downward movement of the cross bar 24 causes lever 27 through the action of release bar 26 to rock shaft 18 and thereby move cam 17 out from 20 under lug 16 as the driver contacts the box part. Continued movement of the driver will then force the box part X, prong P and plate 10 downwardly toward the block 11 and the clincher block 15, and the prong P will be clinched as 25 shown in Fig. 8.

Shaft 18 extends through all the clincher units and it is necessary to have but one release bar 26 to actuate it, as shown in Fig. 2.

When the driving and clinching operations are completed and the cross bar 24 raised to initial position, springs 12 will raise plate 10 to initial position and spring 20 will move cam 17 into position beneath the lug 16 to resist positively 30 the next thrust of the driver.

Among other advantages the clinching mechanism of this application insures a satisfactory and uniform clinching operation regardless of wide variations in the type of character of wood used in the manufacture of boxes.

While one clincher unit only has been shown and described in detail, it will be understood that a clincher unit is provided for each wire to be operated upon, the several clinching units being adjustable to accommodate different wire spacings, all as described in the patents hereinbefore referred to.

While the clinching mechanism of this application has been described as adapted for use in the particular type of machine shown in the 50 aforesaid Patents No. 1,933,031 and No. 2,024,188, it will be understood that it may be used to advantage in other machines designed to clinch the ends of wires driven through box parts.

It will also be understood that the invention is 55 not to be limited to the specific embodiment shown for purposes of illustration as it may be variously embodied without departing from the invention.

It will also be understood that all of the features of the invention need not be used conjointly as 60 they may be used to advantage in various combinations as defined in the sub-joined claims.

I claim:

1. In a machine of the character described, instrumentalities operable upon a wire secured to a box part to bend the wire to form a bight, means to drive the end of the wire through the box part to perpetuate the bight, and means to clinch the end of the wire which is driven through the box part; said clinch means comprising a clinch block, means yieldingly to support the box part above the clinch block, means positively to support the box part above the clinch block, and means to release the positive support after the wire has been driven through the box part to per-

mit the driver to force the wire end against the clinch block.

2. In a machine of the character described, instrumentalities operable upon a wire secured to a box part to bend the wire to form a bight, means to drive the end of the wire through the box part to perpetuate the bight, and means to clinch the end of the wire which is driven through the box part; said clinch means comprising a clinch block, 10 means yieldingly to support the box part in spaced relationship to the clinch block, means positively to support the box part in spaced relationship to the clinch block, and means to release the positive support after the wire end has been driven 15 through the box part to permit the driver to force the wire end against the clinch block.

3. In a machine of the character described, instrumentalities operable upon a wire secured to a box part to bend the wire to form a bight, means 20 to drive the end of the wire through the box part to perpetuate the bight, and means to clinch the end of the wire which is driven through the box part; said clinch means comprising a clinch block, yielding means normally supporting the box 25 part above the clinch block, means positively to support the box part above the clinch block, and means to release the positive support after the wire end has been driven through the box part to permit the driver to force the wire end against 30 the clinch block.

4. In a machine of the character described, instrumentalities operable upon a wire secured to a box part to bend the wire to form a bight, means to drive the end of the wire through the box 35 part to perpetuate the bight, and means to clinch the end of the wire which is driven through the box part; said clinch means comprising a clinch block, yielding means normally holding the box part in spaced relationship to the clinch block, 40 means positively to hold the box part in spaced relationship with the clinch block, and means to withdraw the positive support during a driving operation.

5. In a machine of the character described, instrumentalities operable upon a wire secured to a box part to bend the wire to form a bight, means to drive the end of the wire through the box part to perpetuate the bight, and means to clinch the end of the wire which is driven through the box 45 part; said clinch means comprising a clinch block, yielding means normally holding the box part in spaced relationship to the clinch block, means positively to hold the box part in spaced relationship with the clinch block and means to withdraw 50 the positive support during a selected phase of the driving operation.

6. In a machine of the character described, instrumentalities operable upon a wire secured to a box part to bend the wire to form a bight, means 60 to drive the end of the wire through the box part to perpetuate the bight, and means to clinch the end of the wire which is driven through the box part; said clinch means comprising a clinch block, yielding means normally holding the box 65 part in spaced relationship to the clinch block, means positively to hold the box part in spaced relationship with the clinch block, and means operated in accordance with the position of the driver to withdraw the positive support.

7. In a machine of the character described, instrumentalities operable upon a wire secured to a box part to bend the wire to form a bight, means 70 to drive the end of the wire through the box part to perpetuate the bight, and means to clinch the 75 end of the wire which is driven through the box

part; said clinch means comprising a clinch block, a spring support for the box part means positively to support the box part above the clinch block, and means to release the positive support during a driving operation.

8. In a machine of the character described, instrumentalities operable upon a wire secured to a box part to bend the wire to form a bight, means to drive the end of the wire through the box part to perpetuate the bight, and means to clinch the end of the wire which is driven through the box part; said clinch means comprising a clinch block, a spring support for the box part, means positively to support the box part above the clinch block, and means operated in accordance with the position of the driver to withdraw the positive support.

9. In a machine of the character described, instrumentalities operable upon a wire secured to a box part to bend the wire to form a bight, means to drive the end of the wire through the box part to perpetuate the bight, and means to clinch the end of the wire which is driven through the box part; said clinch means comprising a clinch block, a spring support for the box part, means positively to support the box part in spaced relationship to the clinch block, and means to release the positive support at selected times.

10. In a machine of the character described, instrumentalities operable upon a wire secured to a box part to bend the wire to form a bight, means to drive the end of the wire through the box part to perpetuate the bight, and means to clinch the end of the wire which is driven through the box part; said clinch means comprising a clinch block, a spring support for the box part, means positively to support the box part in spaced relationship to the clinch block, means normally holding said support in operative position, and means to move it to inoperative position.

11. In a machine of the character described, instrumentalities operable upon a flexible binder secured to a box part to bend the binder to form a bight, means to drive the end of the binder through the box part to perpetuate the bight, and means to clinch the end of the binder which is driven through the box part; said clinch means comprising a clinch block, means yieldingly to support the box part above the clinch 45 block, means positively to support the box part above the clinch block, and means to release the positive support at selected times.

12. In a machine of the character described, instrumentalities operable upon a flexible binder secured to a box part to bend the binder to form a bight, means to drive the end of the binder through the box part to perpetuate the bight, and means to clinch the end of the binder which is driven through the box part; said clinch means comprising a clinch block, a spring support for the box part, means positively to support the box part in spaced relation to the clinch block, and means to release the positive support at selected times.

13. In a machine of the character described, instrumentalities operable upon a plurality of wires secured to a box part to bend each wire to form a bight, means to drive the end of each wire through the box part, and means to clinch the ends of the wires which are driven through the box part; said clinch means comprising a plurality of clinch blocks, means yieldingly to support the box part above the clinch blocks, means positively to support the box part above 70 the ends of the wires which are driven through the box part; said clinch means comprising a plurality of clinch blocks, means yieldingly to support the box part above the clinch blocks, means positively to support the box part above 75

the clinch blocks, and means to release the positive support at selected times.

14. In a machine of the character described, instrumentalities operable upon a plurality of wires secured to a box part to bend each wire to form a bight, means to drive the end of each wire through the box part, and means to clinch

5 the ends of the wires which are driven through the box part; said clinch means comprising a plurality of clinch blocks, a spring support for the box part, means positively to support the box part in spaced relation to the clinch blocks, and means to release the positive support at selected times.

15. 15. In a machine of the character described, instrumentalities operable upon a wire secured to a box part to bend the wire to form a bight, means to drive the end of the wire through the box part to perpetuate the bight, and means to clinch the end of the wire which is driven

through the box part; said means comprising a stationary clinch block, yielding means normally holding the box part in spaced relationship to the clinch block, means positively to hold the box part in spaced relationship with the clinch block, and means to withdraw the positive support during a driving operation. 5

16. In a machine of the character described, instrumentalities operable upon a wire secured to a box part to bend the wire to form a bight, 10 means to drive the end of the wire through the box part to perpetuate the bight, and means to clinch the end of the wire which is driven through the box part; said clinch means comprising a stationary clinch block, means positively to support the box part above the clinch block, and means to release the positive support during a driving operation. 15

ALFRED L. ROSEN MUND.
